CLAIM

The ornamental design for an active stylus as shown and described.

DESCRIPTION

FIG. 1 is a perspective view of an active stylus, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing a using status of an active stylus;

FIG. 10 is another perspective view in using status thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is an enlarged view of portion 17 shown in FIG. 9. The dash-dash broken lines in the drawings depict portions of the active stylus that form no part of the claimed design. The dot-dash broken lines represent boundaries of the enlarged portion and form no part of the claimed design. The dot-dash broken lines represent the designation of enlargement views and form no part of the claimed design.

1 Claim, 17 Drawing Sheets
